6 Claims. (Cl. 131—45)

For the production of shaped cigars, that is to say cigars having pointed or non-cylindrical ends, it has already been proposed to shape the rollers of a nest of bunch rollers correspondingly. With this end in view it has already been contemplated to form the rollers of a plurality of parts, for instance a cylindrical main part and two end parts of conical or like formation, the principal axes of which were arranged at an angle to the axis of the middle, cylindrical part.

It has been found impossible to produce a satisfactory cigar with the nests of bunch rollers hitherto known, particularly as the wrapper cannot be applied to the shaped ends of the bunch, by mechanical means, as tightly and as efficiently as by hand. This is due to the fact that all of the shaped bunch rollers hitherto known are to a certain extent rigid and in any case are unable to conform sufficiently to the shape of the bunch.

In contrast to the above, the present invention consists in that for the application of the wrapper to the pointed or similarly shaped end of the bunch, a pair of jaws separate from the bunch rollers and shaped to correspond to the ends of the cigars, is provided, which applies a flexible pressure and grips the end of the bunch while pressing on the wrapper.

In order that the shape of the cigar tip may be followed with the greatest exactitude, each pair of jaws is preferably composed of separate, independently flexible laminations.

One form of construction of the invention is illustrated in the annexed drawings, in which:

Fig. 1 is a front view.

Fig. 2 is a side view thereof.

Fig. 3 is a partial plan.

Fig. 4 shows a part of the arrangement illustrated in Fig. 1 when the parts are in another position.

Figs. 5^a and 5^b are detailed views.

The nest of rollers, of known type, is formed of lower rollers 1 and upper rollers 2. The axles 1' of the lower bunch rollers are mounted in the machine frame and the bunch rollers 2 are mounted in bearings 3, which are pivotally mounted on the axle 1', and each opposite pair of which is held together by a rod 4. The bunch rollers are driven by the main driving shaft 5 which is connected by gear wheels 6 and 7 with an axle 8 mounted in the machine frame. The spur wheel 7 is mounted on the same axle as a spur wheel 9 with which gear wheels 1'' of the lower bunch rollers engage. By means of intermediate wheels 10, the gear wheels 1'' are connected with gear wheels 2'' which are mounted

on the axles 2' of the upper bunch rollers 2. On the machine frame G is mounted a bearing arm 11 which carries a pivot 12 for a pair of jaws 13, 13' which are shaped in conformity with the end of the cigar, and the ends 13' of the said jaws overlapping each other hinge-wise. At 13'' a spring 14 engages the lower limbs of the pair of jaws 13 and tends to keep them in the position shown in Fig. 1, wherein the jaws are in the closed position and the space between the jaws corresponds to the tip of the cigar to be covered with the wrapper. Between the limbs 13' is arranged a roller 15, which is mounted on a double-armed lever 16. The double-armed lever is mounted on the frame at 17 and, under the tension of a spring 18, is drawn with a roller 19, also mounted on the lever 16, against a cam 20 which is mounted on the main axle. It is a known fact that the upper bunch rollers 2 must be swung apart while the bunch is being inserted in the bunch nest. For this purpose the bearing arms 3 are provided with levers with which links 22 engage at 21', these links being connected to a lever 24 by a common pin 23. The lever 24 is mounted on the machine frame at 25, and under the tension of a spring 26 is brought, with a roller 27 mounted thereon, into contact with a cam 28 which is mounted on the main shaft.

The mode of operation of the apparatus is as follows:—

As soon as a cigar has been prepared in the nest of rollers, the link mechanism 21 to 24 is moved in such manner that the upper bunch rollers 2 assume the position shown in Fig. 4. At the same time, the cam 20 causes the lever 16 to swing about the pivot 17 against the tension of the spring 18 in such manner that the roller 15 is moved downwards and the limbs 13' are moved apart, so that the jaws 13 assume the position shown in Fig. 4. Thereupon the finished cigar can be removed from the nest of rollers and a new bunch W inserted. At the same time the front end of the wrapper D is placed in the position indicated in Figs. 3 and 4. Then the cam 20 swings the lever 16 into the position shown in Fig. 1, so that the jaws 13, under the tension of the spring 14 can be placed around the cigar end, at the same time applying the wrapper. After the bunch rollers 2 have been brought into the operative position by the cam 28, the bunch is set in rotation between the jaws 13 in a manner similar to the application of the wrapper between the fingers of the cigar maker. Thus in known manner, the wrapper carrier (not shown in the drawings) fol-

lows the continuous helical winding of the wrapper about the bunch.

In the form of construction shown in Figs. 1-4, two rigid jaws are used. It is, however, also possible, as shown in Fig. 5, for the jaws to be subdivided into laminations, each pair of laminations being associated with a spring which causes the individual laminations to be pressed against the bunch. Thus, in this arrangement it is not necessary for a special pair of jaws to be arranged for each special shape of cigar, as the sub-division into separate laminations renders it possible for the individual pairs of laminations to conform to the pointed shape of the cigar bunch. It is obvious that in the last-mentioned type of construction the opening of the separate pairs of laminations can be effected by a single control roller 15'.

Having thus described the nature of the said invention and the best means I know of carrying the same into practical effect, I claim:—

1. An apparatus for applying a cigar wrapper to a bunch comprising bunch rollers, a pair of pivoted jaws located adjacent one end of said bunch rollers and flexible means normally urging said jaws together to exert a flexible pressure to hold an end of the wrapper to the end of said bunch to secure a correct application of said wrapper to said bunch at the start of the wrapping operation.

2. An apparatus for applying a cigar wrapper to a bunch comprising bunch rollers, a series of pivoted jaws located at one end of said bunch rollers and flexible means normally urging said jaws to closed position to secure an end of said wrapper to the end of said bunch to secure a cor-

rect application of said wrapper to said bunch at the start of the wrapping operation.

3. An apparatus for applying a cigar wrapper to a bunch comprising bunch rollers, a pair of laminated jaws located adjacent said bunch rollers, flexible means for normally urging the laminations of said jaws to closed position to apply an end of said wrapper to the end of said bunch to secure a correct application of said wrapper to said bunch at the start of the wrapping operation.

4. An apparatus for applying a cigar wrapper to a bunch comprising bunch rollers, pivoted jaws located adjacent said bunch rollers, flexible means for normally holding said jaws in closed position and a cam operated roller for opening said jaws to allow of the insertion of the end of a wrapper.

5. An apparatus for applying a cigar wrapper to a bunch comprising fixed rotating lower bunch rollers, pivoted upper bunch rollers for cooperating with said lower rollers, cam means for moving said upper rollers to the side of said lower rollers to allow of the insertion of a bunch, pivoted jaws located adjacent said bunch rollers, flexible means normally holding said jaws in closed position and means for opening said jaws at approximately the same time as said upper rollers are moved to the side of said lower rollers.

6. An apparatus for applying a cigar wrapper to a bunch comprising bunch rollers, a pair of laminated jaws located adjacent said bunch rollers, flexible means for urging normally individual laminations to closed position and a common means for simultaneously opening all of said laminations.

CONSTANTIN FRIEDRICH RÖBER.
